CLAIM

The ornamental design for a tablet holder for use in vehicle,
as shown and described.

DESCRIPTION

FIG. 1 is a top, front, right side perspective view of a tablet
holder for use in vehicle, showing my new design;

FIG. 2 is a bottom, rear, left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view showing the tablet holder for
use in vehicle in unfolded state; and,

FIG. 10 in an enlarged view of portion 10 in FIG. 9.

The evenly dashed broken lines illustrate portions of the

tablet holder for use in vehicle that form no part of the

(Continued)

claimed design. The unevenly dashed broken lines define the boundaries of enlarged views and form no part of the claimed design.
